UNITED STATES PATENT OFFICE.

GEORGE HAVILAND, OF LIMOGES, FRANCE.

DESIGN FOR A BOWL OR SIMILAR ARTICLE.

59,218.

Specification for Design.

Patented Oct. 4, 1921.

Application filed May 16, 1921. Serial No. 470,022. Term of patent 14 years.

To all whom it may concern:

Be it known that I, GEORGE HAVILAND, a citizen of the United States, residing at Limoges, France, have invented a new, original, and ornamental Design for a Bowl or Similar Article, of which the following is a specification, reference being had to the accompanying drawing, forming a part thereof, and in which:—

I claim: The ornamental design for a bowl or similar article, as shown.

GEORGE HAVILAND.
